JACK

Sigmund Mandl and Edward M. Pfauser, Milwaukee, Wis., assignors to Blackhawk Mfg. Co., Milwaukee, Wis., a corporation of Wisconsin

Application April 12, 1933, Serial No. 665,675

23 Claims. (Cl. 254—6)

The present invention relates generally to lifting jacks and is particularly concerned with jacks used around garages, repair shops and the like for raising one end of an automobile and supporting the same in elevated position. Obviously, however, such jacks have other uses.

One of the principal objects of the present invention is the provision of a lifting jack which is of small height so that the jack can be moved under very low objects, such as extremely low automobile axles, and can then be actuated to raise the load to a considerable height.

In the modern automobile of the type manufactured today, the axles are quite low, due to the general trend of providing a low center of gravity and a relatively small road clearance, and the modern automobile also is generally equipped with extremely low fenders and aprons set a considerable distance ahead of or from the axles. In order to raise the car it is preferable, of course, to engage the axle, and in order to do this the jacks used for lifting and moving cars must, first of all, be low enough to be moved in under and clear all overhanging parts and, moreover, must be low enough so as to engage the low hung axles or other portions of the automobile by which the latter is lifted.

Another object of the present invention is the provision of a jack of this type in which the height of the lift is relatively great, being high enough to elevate the automobile to a considerable height and also to engage and lift automobiles of older types wherein the axles are at a greater height above the ground.

Briefly, the present invention contemplates the provision of a jack having the above mentioned low height high lift features and wherein the lifting member is in the form of a lifting arm of the cantilever type in which there is a long arm for lifting the load and a short arm to receive the application of power. As is obvious, the longer the lifting arm the greater the height, and the shorter the power arm the lower to the floor the jack can be built. That is to say, the shorter the power arm the lower the fulcrum or pivot point of the cantilever lifting member can be positioned.

Mechanical floor jacks for automobiles and the like are usually arranged for manual operation, and in this case where a relatively short power arm is employed, it is necessary to provide for the greater power required where the power arm is relatively short. The present invention meets these requirements by providing an improved form of reduction gear whereby, while accom-

modating manual operation, sufficient power is developed to enable the jack to raise the heaviest automobile. The provision of such reduction means forms therefore, another of the important objects of the present invention.

More specifically, another object of the present invention, with a view of providing an extremely low lifting jack, is the provision of a frame or equivalent supporting means for the jack wherein in the fulcrum or pivot point for the lifting arm is low and wherein the upper edges of the frame are substantially straight and horizontal, that is to say, the fulcrum for the lifting arm is disclosed adjacent the upper horizontal edge of the jack frame, but is not materially higher, to facilitate moving the jack into position under low overhanging parts of the car. In some lifting jacks of the prior art, the fulcrum is disposed on a casting or the equivalent which extends to a point substantially above the upper edges of the side frame plates, and this fulcrum support frequently collides with portions of the car body when an attempt is made to move the jack underneath the car. Under such conditions the jack is practically useless. Such disadvantages and objections are avoided in the present construction.

Another object of the present invention is the provision of a lifting jack wherein a relatively great amount of power, required for swinging a long lifting arm by means of a relatively short power arm, is obtained in a simple and convenient construction embodying mechanical parts which are compact and simple in construction and appearance.

Still further, another object of the present invention is the provision of longitudinally disposed parts, specifically, relatively movable horizontally disposed racks with an interposed floating pinion, for securing the aforesaid reduction. In addition, another object is the provision of parts particularly adapted to resist the reactions established in the development of such power.

Another object of the present invention is improved means for controlling the raising and lowering mechanism, which controlled means is designed as a relatively low compact and simple unit enclosed by suitable housing means and disposed at the end of the frame opposite the lifting member.

Still further, another object of the present invention is the provision of means securing an extra reduction between the operating handle and the lifting member, which extra reduction is secured by parts which are disposed and which operate efficiently in a horizontal position on the

jack frame, by virtue of which construction the height of the jack above the floor is not increased by the provision of means securing the extra reduction.

5 Further, another object of the present invention has to do with the design of the raising and lowering mechanism. According to the principles of the present invention the stresses involved in the lifting operation are imposed on 10 parts designed to take such stresses and in such a manner that as much eccentricity is avoided as possible. In this way, the stresses imposed are imposed directly on the parts concerned, with the result that there is little likelihood of the 15 operating mechanism getting out of line and, likewise, other maladjustments are avoided.

These and other objects of the present invention will be apparent from the following description of an illustrative structure in which the 20 principles of the present invention have been embodied, in connection with the accompanying drawings illustrating such embodiment.

In the drawings:

Figure 1 is a side elevation of a lifting jack 25 embodying the principles of the present invention and showing the position of the lifting member in elevated position in dotted lines;

Figure 2 is an enlarged longitudinal vertical section taken through the raising and lowering 30 mechanism, and corresponding to a section taken along the line 2-2 of Figures 5 and 8;

Figure 3 is a longitudinal section taken along the line 3-3 of Figure 5, but on a somewhat smaller scale than Figure 2, and illustrating the 35 rack and pinion means embodied in the raising and lowering mechanism;

Figure 4 is a section taken substantially along the line 4-4 of Figure 3;

Figure 5 is a section taken substantially along 40 the line 5-5 of Figure 3;

Figure 6 is an enlarged section taken through the foot operated speed-up mechanism for quickly elevating the lifting member up into contact with its load;

Figure 7 is a section taken along the line 7-7 45 of Figure 6;

Figure 8 is a section taken along the line 8-8 of Figure 2, but on a somewhat smaller scale; Figures 9 to 12, inclusive, are views corresponding to Figure 2 and showing the slideable reversing plate in its different positions; and

Figure 13 is an enlarged sectional view showing the rotatable saddle for engaging and supporting the load.

55 Referring now to the drawings, particularly Figure 1, the illustrated lifting jack in which the principles of the present invention have been embodied comprises a front or lifting end 10 disposed at the front of an elongated frame 11 and lifting mechanism enclosed within a housing 12 at the opposite end of the frame 11 from the lifting end 10. The housing 12 preferably forms a part of the frame 11 and the whole, as a unit, is supported on wheels 13 and 14. The 60 frame may be a casting or may be fabricated of several parts suitably secured together. The mechanism at the lifting end of the frame is more or less conventional in construction and embodies a saddle member 15 carried by or pivotally connected with the outer end of a lifting member in the form of a relatively long cantilever lifting arm 16. The lifting arm or member is pivotally supported on a fulcrum pin or stud 17 which is carried by the frame 11 adjacent the horizontal upper edge thereof, and the

lifting member also includes a relatively short power arm 18. It will thus be seen that the arms 16 and 18 comprise a lifting bell crank at the outer end of which the saddle 15 is pivotally connected.

As best shown in Figure 13, the saddle 15 preferably consists of a load receiving head 19 having a shank 21 rotatably carried by a saddle bracket 24 and maintained therein by a pin 25 engaging a groove 26 formed on the shank 21 and locked in the bracket 24 by a set screw 27 or the equivalent. The pin 25 may also be used to pivotally connect the link or lifting arm 16 with the saddle member 15.

10 In order to maintain the saddle 15 in horizontal position a pair of links 20 are pivotally connected, as at 22, with the frame 11 at each side thereof, the links also being pivotally connected, as at 23, with an extension of the saddle member 15. The links 20, in connection with the relatively long 20 lifting arm 16, constitute parallel link mechanism. The position of these parts in Figure 1 in which the reference numerals have been applied to them is the lowered position, and it will be noted that the lowered position of the saddle 25 member 15 is substantially at the level of the front supporting wheels 13. It will also be noted that the frame 11 is so formed that its upper edge is substantially horizontal and that the fulcrum support 17 does not extend any material extent 30 above the upper edge of this member. Likewise, the position of the saddle 15, when lowered, is substantially in the same horizontal plane as the fulcrum 17. This, as will be observed, provides a lifting jack in which the fulcrum 17 is low enough 35 to clear all overhanging skirts, fenders, aprons, and other body parts of the automobile when disposing the saddle member 15 underneath the axle or some other part of the car to be raised.

With the advent of tires of large cross-section, 40 popularly known at the present time as air wheels, and with the advent of stream lining and low hung body parts, the provision of a lifting jack in which the fulcrum 17 is quite close to the floor is extremely important. Looking at Figure 1, for 45 example, it will be observed that the jack can be used and can be inserted under any low load under which the saddle member 15 can itself be disposed.

One of the means securing this result is, as 50 mentioned above, the provision of the relatively short power arm 18. By power arm is meant the portion of the bell crank 16-18, to which force is applied to raise the saddle member 15. In view of the fact that older types of cars employed axles 55 having considerably greater road clearance, and also in view of the fact that it is sometimes desirable to be able to raise one end of the automobile to a considerable height, it is necessary that the lifting arm 16 be of substantial length in order to 60 obtain the required lifting range. As a result of these two factors, it will be observed that the construction involves or requires means capable of exerting a relatively great amount of force on the power arm 18 in order to be able to conveniently 65 and quickly handle the load. The present invention contemplates means capable of exerting a considerable force, in fact, a much greater force for this purpose than the lifting jacks of the prior art of which we are aware.

70 The lowermost end of the power arm 18 carries a pivot pin 30 to which is pivotally connected a thrust bar or member 31 which extends, as will be seen from Figure 1, rearwardly and slightly upwardly. Referring now to Figures 3 and 4, it 75

will be observed that this thrust member comprises a pair of thrust rods or bars 33 disposed substantially centrally of the frame 11 and terminating rearwardly at a point where the bars 33 are apertured to receive a pin or shaft 35 on which a floating pinion 36 is disposed. The floating pinion is enclosed within the housing 12, and this housing is also formed with bosses or flanges 38 between which is disposed stationary reaction members or abutment bars 39 and a stationary rack 40 having teeth 41 with which the teeth of the floating pinion 36 mesh. As will be seen from Figure 8, the pinion 36 is disposed between the two stationary reaction bars 39 and that the bars 33 are, at their rearmost ends, disposed in contact with the lower edges of the reaction bars 39.

The housing or casing 12 is formed of two sections 45 and 46, separable along the line 47, so as to facilitate properly machining the casing parts and also to facilitate assembling the raising and lowering operating mechanism.

The lower housing section 46 forms the bottom of the casing 12 and is provided with a longitudinally extending elevated portion 50 which is formed to provide ways 51 and guiding flanges 52 (Figures 4 and 8) for slidably receiving a longitudinally shiftable rack member 55. This rack member is meshed with the floating pinion 36, as best shown in Figure 3, and from this figure it will be seen that if the rack bar is shifted, to the left in Figure 3, for example, the pinion 36 will be caused to roll along the relatively stationary rack 40, thus advancing the thrust bars 33 at a rate which is equal to half the peripheral velocity of the pinion 36 at its lower portion, which corresponds, of course, with the rate of movement of the shiftable rack 55.

By virtue of this construction, it will be observed that the rack members 40 and 55 are disposed in a horizontal position and that the pinion 36 is relatively small so that the overall height of these parts is small. Nevertheless, by virtue of this construction alone, a two to one reduction is provided. The stationary rack 40, which is approximately only one-half the length of the rack 55 but of the same tooth form, is secured in the upper part of the upper housing section 45 by means of pins 60 or the equivalent disposed in suitable openings in the bosses 38. These pins are also utilized as the supporting means for the reaction bars 39.

Since the rear ends of the bars 33 are in contact with the reaction bars 39 and since the bars 33 are disposed in the downwardly and forwardly inclined position, it will be seen that the reaction thrust of the load on the saddle member 15, acting through the bell crank 16-18, causes the upper ends of the bars 33 to bear against the reaction bars 39. In this way the pinion 36 is relieved of all such strain, the contact between the thrust bars 33 and the reaction bars 39 serving, therefore, to maintain the pinion 36 in proper position with respect to the rack 40 with which it meshes. Likewise, the pinion 36 is maintained in proper position with respect to the shiftable rack 55. If desired, the pinion 36 may be designed with teeth that bottom in the rack 40 so as to take the vertical reaction, in which case the bars 39 may be omitted.

Any known means may be provided for shifting the shiftable rack 55, but in this type of lifting jack it is desirable that, whatever the means employed, such means should not have an excessive over-all height but should be low with respect to the supporting surface. In the preferred form

of the present invention ratchet mechanism is provided for shifting the rack 55, and preferably this ratchet mechanism includes a pinion meshing with the rack 55, which pinion is identical, for all practical purposes, with the pinion 36. Since these pinions are of the same tooth form, the construction and manufacture is greatly simplified since the portion of the rack which engages the pinion 36 and the portion which engages the ratchet pinion, later to be described in detail, can be formed in one and the same rack. The jack can thus be made at less cost since duplicate parts can be employed.

The ratchet mechanism will now be described. The upper section of the housing 12 is formed with bosses 61 at either side thereof, and these bosses rotatably receive a pinion shaft 63 which extends at both ends through the housing or casing section and which is provided with a squared portion 64 intermediate the inner ends of said bosses, as best shown in Figures 4 and 5. The pinion referred to above as being identical with or of the same tooth form as the pinion 36 is indicated by the reference numeral 66 and is either mounted on or provided with a sleeve portion 67 which includes a square opening adapted to be mounted on the squared portion 64 of the pinion shaft 63 in a non-rotatable relation. Obviously, polygonal forms other than squared portions may be employed for this purpose. The teeth of the pinion 66 mesh with the teeth of the rack bar 55, the pinion 66 being disposed closely adjacent the pinion 36, as best shown in Figures 2 and 3, so as to allow the use of a relatively short rack 55.

At one side, the teeth or other portions of the pinion 66 are extended, as indicated by the reference numeral 70, and these extended portions are received within the hub portion 74 of a ratchet wheel 75 provided with ratchet teeth 76. The ratchet wheel 75 is mounted on one end of the squared portion 67 of the pinion 66, being rotatable therewith and with the pinion 66 by virtue of the interengaging parts just described and which serve as means directly connecting the ratchet wheel with the pinion so as to transmit force thereto without stressing either the pinion shaft 63 or the sleeve portion 67.

Means for rotating the ratchet wheel 75 is provided in a form of driving pawl means carried for limited oscillation about an axis concentric with the axis of the ratchet wheel by a swinging quadrant disposed within the upper section 45 of the housing 12. The quadrant is indicated in its entirety by the reference numeral 80 and, as best shown in Figures 4 and 5, the quadrant 80 includes laterally spaced arm portions 81 and 82 provided with suitable bearing portions 84 and 85, the latter portion being mounted directly on one end of the sleeve 67 of the pinion 66 while the bearing portion 84 of the quadrant 80 is journaled for rotation on the hub portion 74 of the ratchet wheel 75. It will be noted from Figures 4 and 5 that all of this mechanism is assembled within a narrow compass and all parts are enclosed by the housing or casing 12.

The driving pawl means proper is indicated by the reference numeral 90 and comprises a driving pawl 91 rotatably mounted on a pivot shaft 92 suitably pinned or otherwise fixed to a sleeve portion 93 of the quadrant 80 connecting the arms 81 and 82. Spring means 95 of any suitable character may be provided for biasing the pawl 91 for movement toward the ratchet teeth 76, as best shown in Figure 2.

The upper portions of the arms 81 and 82 are 75

extended outwardly through a slot 100, as indicated in Figure 4, and are joined together by a connecting portion 102 having a plurality of openings 103 formed therein in which suitable manually operated means is adapted to be engaged. The portions of the arms 81 and 82 which are extended upwardly are connected together by a transversely disposed web portion 105, best shown in Figures 3 and 4. The connecting portion 102 of the quadrant is extended in a generally fore and aft direction so as to practically cover the slot 100 in the housing 12. The connecting portion 102 is also extended laterally for the same purpose, as best shown in Figure 4.

15 The manually operated means referred to above as engageable with the quadrant 80 includes a vertically swinging handle 110 terminating at its lower end in a yoke 111 having arm portions 112 and 113 which are journaled on the 20 extended ends of the pinion shaft 63, as best shown in Figures 4 and 5. The intermediate portion of the yoke 111 is disposed closely adjacent the apertured connecting portion or head 102 of the quadrant 80, and suitable plunger 25 means 118 is slidably carried by the handle 110 and is adapted to be engaged in any one of the openings 103 formed in the exterior portions of the quadrant 80. The plunger 118 is provided with a shoulder 119 engageable with one of the 30 webs 120 of the handle 110 to limit the inward movement of the plunger 118. A spring 123 or the equivalent may be provided for biasing the plunger 118 for movement toward engaging position with the quadrant 80.

35 A cover 125 is provided for enclosing the shiftable rack 55 so as to prevent the operator and other persons or objects from coming into contact with this rack. The cover 125 comprises a rectangular section having a lower open side 40 126 and an upwardly curved tongue 127 which is curved, as best shown in Figure 3, to correspond with the curvature of the upper section 45 of the casing. The tongue 127 is also arranged to be disposed underneath the apertured head 45 102 of the quadrant 80 and in between the lateral arm portions 81 and 82 thereof, as best shown in Figure 4. At its end, the tongue 127 of the rack cover 125 is suitably threaded to receive an attaching screw 129 or the equivalent. Obviously, 50 any other means for mounting the rack cover 125 in position on the casing or housing 12 may be provided if desired.

As will be clear from the above description, the plunger 118 of the handle 110 may be engaged in any of the openings or slots 103. Vertical oscillations of the handle 110 will then be effective for turning the ratchet wheel 75 by virtue of the engagement of the driving pawl 91 with the teeth 76. In this construction it is necessary to provide some means for holding the ratchet wheel against retrograde rotation. Such means may conveniently take the form of a holding pawl 130 mounted upon a fixed pawl pinion shaft 131 suitably pinned or otherwise mounted in a boss 132 provided in the lower section 46 of the casing 12. A spring 133 or the equivalent serves to hold the pawl 130 up against the teeth 76 of the ratchet wheel 75.

70 Swinging the handle 110 downwardly in the direction of the arrow shown in Figure 2 will cause the driving pawl 91 to engage one of the teeth of the ratchet wheel and will therefore rotate the pinion 66 by virtue of the direct connection between the ratchet wheel 75 and the pinion. 75 In this connection it is important to note that

no torque is transmitted through the pinion shaft 63. During rotation of the ratchet wheel 75 in the direction of the arrow, the teeth 76 will ride over the holding pawl 130, but the latter is biased for movement into engagement therewith and will therefore serve to hold the ratchet wheel 75 in any position of forward advance. Rotation of the pinion 66 serves to shift the slideable rack member 55 toward the left as viewed in Figures 2 and 3 and will roll the floating pinion 36 toward the left along the fixed rack 40. Thus, the thrust member 33 will be advanced to swing the lifting arm 16 upwardly, the extent of movement of the thrust member 33 being one-half the extent of movement of the rack 55.

15 It is important to note that both the driving pawl 91 and the holding pawl 130 are disposed underneath the ratchet wheel 75. By virtue of this construction the overall height of the rear end of the jack is kept down to a desirable minimum.

20 As will be apparent from the above description, vertical oscillations of the handle 110 will cause, first, the pawl 91 to engage one of the teeth 76 on the ratchet wheel 75 so that as the handle 110 is swung downwardly the ratchet wheel 75 will be advanced, and next the pawl 130 will be engaged with one of the teeth 76 to hold the ratchet wheel in that position against retrograde movement while the handle 110 is swung upwardly, 25 the driving pawl now idly riding over the teeth 76 to its new position of engagement with the ratchet wheel 75. Upon a second downward movement of the handle 110 the ratchet wheel will again be advanced. In this manner an intermittent forward rotation will be imparted to the ratchet wheel 75 so that the shiftable rack 55 will cause the thrust member 31 to be advanced to raise the load supported on the saddle 15.

30 In mechanism of this sort it is, of course, necessary to provide some sort of means for reversing the above operations so that the saddle 15 and the load supported thereon may be lowered under the control of the operator. Such means will now be described.

35 A reversing plate 150 is slidably supported on the upper casing part 45 by means of pins 151 disposed within slots 152 formed in the reversing plate 150. The slideable reversing plate 150 is provided with a plurality of cam portions 40 155 and 156 which are adapted to engage, respectively, with projecting studs 159 and 160 formed on or carried by the holding and driving pawls 130 and 91, respectively, whereby the reversing plate 150 can control the driving and holding pawls. A spring 161 is anchored to one end of the reversing member 150 and to a stud 162 carried by the casing 12 and serves to continuously bias the reversing member 150 for forward movement, which is toward the left as 45 viewed in Figures 2 and 9 to 12, inclusive.

50 When the ratchet mechanism is to be actuated to raise the lifting member 16, it is necessary to hold the reversing member 150 out of contact with the lugs 159 and 160 on the holding and lifting pawls and against the tension of the spring 161. Means for performing this function preferably takes the form of a lockout member 165, comprising a shaft 166 carrying a locking arm 167 at one end and an operating pedal 168 at the other end, as best shown in Figures 2 and 5. The locking arm 167 is provided with a stud 170 disposed in the plane of the reversing plate 150, as best shown in Figure 5, and this locking stud is adapted to cooperate with a third cam 55 60 65 70 75

section 171 formed on the rearmost portion of the reversing plate 150 and being of the form shown in Figures 2 and 9 to 12. This third cam section is recessed, as at 172 and 175 in Figures 5, 2, 10 and 11, to accommodate both the engaged and released positions of the locking stud 170. When the locking arm shaft 166 is rocked rearwardly, the locking stud 170 contacts with the rear portion 171 of the reversing plate 150, the latter having the portion 175 cut away to accommodate the released position of the locking stud 170. This swinging movement of the arm 167 moves the reversing plate 150 against the tension of the spring 161 from a position, such as that shown in Figures 11 and 12, to the position indicated in Figure 2 in which the cam sections 155 and 156 are entirely free of the lugs or studs 159 and 160 on the holding and lifting pawls. In this position the locking stud 170 moves into 20 the curved recess 172 to effectively lock the cam plate 150 in retracted position. When the holding and driving pawls are thus released from the control of the plate 150, oscillations of the handle 110 serve to advance the ratchet 75 to 25 raise the lifting saddle 15 as described above. It is important to note that as long as the reversing member 150 is held in its inoperative or rearward position, see Figure 2, the oscillations of the pawls 91 and 130 are not interfered with. 30 When it is desired to lower the lifting saddle 15, the locking shaft 166 is rocked forwardly, that is, toward the left as viewed in Figure 2, this motion, first moving the locking plate 150 rearwardly slightly until the stud 170 enters the 35 space 175 at the rear end of the reversing member 150. Actually, as soon as the stud 170 has cleared the curved recess 172, the spring 161 becomes immediately effective to shift the reversing member 150 forwardly, carrying with it the locking arm 167 and moving the same to the position indicated in Figure 9. In this position the holding pawl 130 will be sustaining the load on the ratchet so that while the spring 161 will throw 40 the reversing plate 150 forwardly and up against the lug 159 the strength of the spring 161 is not sufficient to forcibly move the holding pawl 130 out of engagement from the ratchet teeth. Thus, 45 the reversing member 150 is merely moved up against the stop lug 159 on the holding pawl 130 and it remains in that position until the handle 50 is swung downwardly slightly so as to cause the driving pawl 91 to engage one of the ratchet teeth and to rotate the ratchet wheel slightly. This will take the load off the holding pawl 130 and 55 as soon as the load is released from the holding pawl, the spring 161 shifts the reversing plate 150 to its forwardmost position, and this movement, by virtue of the cam portion 155 engaging the lug 159 on the holding pawl 130, swings the 60 holding pawl 130 away from the ratchet wheel 75, which is the position shown in Figure 10. As soon as the holding pawl 130 is released and is positively held out of engaging position with respect to the ratchet wheel 75, the lifting handle 65 may be raised to let the load lower, the driving pawl 91 being engaged with the ratchet wheel 75 and sustaining the load. During this movement the driving pawl 91 moves with the ratchet wheel 75, this movement being in the direction of the 70 arrow shown in Figure 11 and is continued until the lug 160 on the driving pawl 91 engages the second cam portion 156 of the reversing member 150, see Figure 11. At this time, since the load is sustained by the driving pawl, the continued 75 upward movement of the handle will cause the lug 160 to move the reversing member 150 rearwardly, to the right as viewed in Figure 11, against the tension of the spring 161. Rearward movement of the reversing member 150, however, will move the cam section 156 away from the holding pawl 130 which will then move into engagement with one of the ratchet teeth on the ratchet wheel 75, as indicated in Figure 11. As soon as the holding pawl is fully engaged with the ratchet teeth it will then take the load on the ratchet, thereby 10 relieving the driving pawl 91 of the load so that lug 160 on the driving pawl will no longer be effective to shift the reversing member 150 against its spring 161, the latter then shifting the high point of the cam section 156 past the lug 160, 15 which throws the driving pawl 91 entirely out of engagement with the ratchet wheel 75, as shown in Figure 12. The parts are so arranged, as shown in Figure 11, that the reversing member 150 is moved by 20 the lug 160 on the driving pawl for some distance rearwardly of the lug 159 on the holding pawl before the latter is fully engaged with the ratchet wheel and before it takes the load of the ratchet wheel from the driving pawl. At the 25 instant, of course, that the holding pawl takes the load and the driving pawl is released, the spring 61 snaps the reversing member 150 forwardly, as mentioned above, from the position indicated in Figure 11 to that shown in Figure 30 12 in which the cam section 155 is drawn into abutting engagement with the lug 159 on the holding pawl 130. This movement of the reversing member 150 shifts the driving pawl 91 out of engagement with the ratchet wheel, by virtue of the cam section 156 acting against the lug 160 on the driving pawl 91. The reversing member 150 moves forwardly to the position shown in Figure 12 in which the lug 160 on the driving pawl 91 engages a dwell portion of the cam section 156. This is 35 40 the extent of upward movement of the handle 110. The next step is to shift the handle 110 downwardly, at which time the driving pawl 91 will be held out of engagement with the ratchet teeth by virtue of the lug 160 moving along the dwell portion of the cam section 156 so that the lifting or driving pawl 91 will be shifted forwardly to 45 a new position before engaging one of the ratchet teeth on the ratchet wheel 75. As soon, however, as the lug 160 engages the inclined portion of the cam section 156 the driving pawl 91 will be moved by the spring 95 upwardly into engagement with the next ratchet tooth, or some other advanced tooth, depending upon the length of the cam section 156 and the amount the cam member 150 moves rearwardly of the lug 159 during upward movement of the handle 110, and then a slight additional downward movement of the handle 110 will transfer the load from the holding pawl 130 again to the driving pawl 91, 50 at which time the holding pawl 130 will then be released by virtue of the spring 161 acting to shift the reversing member 160 to its forwardmost position, this operation being indicated in Figures 9 and 10, and the sequence described above 55 will then be repeated. It is important to note that, by virtue of the sliding cam reversing member 150 and by virtue of the positioning of the driving and holding pawls, as well as the locking member, in the lower portion of the casing 12 and substantially underneath the ratchet wheel 75, a construction 60 is provided wherein the overall height is kept down to a desirable minimum. 75

Reference has been made above to the fact that the casing 12 consists of two separable sections 45 and 46. Preferably, the lower section 46 is detachable from the upper section and is removably secured thereto by stud bolts 180. Preferably, these bolts are disposed in suitable bosses formed on the upper and lower casing sections. Preferably, also, these sections have reinforcing ribs on the interior thereof. The casing sections 10 45 and 46 are preferably in the form of castings and are provided at their forward ends with reduced portions 183 to receive the rear end of the frame section 11. Preferably, although not necessarily, this section is also a casting and is provided 15 with suitable flanges or the like arranged to be secured to the casing 12 by cap screws 185 or the equivalent. By virtue of this construction, it is a relatively simple matter to remove the lower casing section 46 to obtain access to the operating mechanism. It will be observed that certain of 20 the operating mechanism is mounted on the lower section while other parts are mounted on the upper section. This arrangement is desirable in that the assembly of the two sets of operating parts is materially facilitated and the parts are 25 disposed in proper relation when the casing sections are joined together.

As will be clear from the above description one oscillation of the handle 110 moves the 30 ratchet wheel through only one or at least only a few ratchet teeth, this being necessary in order to develop the power required to raise comparatively heavy loads. It is therefore desirable to provide some form of speedup mechanism for 35 quickly raising the saddle 15 up to the point where it begins to engage the load. Such mechanism is shown in Figures 5, 6 and 7 and is attached directly to the pinion shaft 63. This speedup mechanism includes a pedal or operating member 200 pivotally connected, as by a pivot pin 201, with a rotatable casing 203 supported for oscillation on the extended end 204 of the pinion shaft 63. The rotatable casing 203 encloses a toothed wheel 206 which is pinned, as at 40 208, onto the pinion shaft 63 and is rotatable therewith. The operating arm 200 is provided with a nose 211 which is adapted, in one position relative to the casing 203, to engage with one of the teeth on the wheel 206. Normally, however, 45 the arm 200 is held away from engagement with the toothed wheel 206 by virtue of a spring 212 disposed in a socket 213 formed in the arm 200 and reacting against a shoulder 215 formed on the rotatable casing 203.

50 The casing 203 is supported on the pinion shaft 63 for limited oscillation relative thereto and relative to the jack frame, being connected by spring means 216 with a boss 217 formed on the casing 12. The operating arm 200 and the 55 casing 203 are both, as a unit, mounted for pivotal movement with respect to the frame or casing 12. Preferably, the spring means 216 has one end 220 extended into the rotatable casing 203 while the other end is received within a suitable opening in the boss 217 on the casing 12. The strength of the spring 216 is greater than the strength of the spring 212, so that whenever 60 pressure is applied to the operating arm 200 in the direction of the arrow shown in Figure 7, the spring 212 is compressed which allows the nose 211 to engage one of these teeth on the wheel 206. This engages the arm 200 with the wheel 206 so that further pressure on the arm swings the casing 203, the toothed wheel 206 and the 65 pinion shaft 63. This, as will be obvious, rotates

the pinion 66 and the ratchet wheel 75 associated therewith and advances the slideable rack 55 to quickly raise the saddle 15 into engagement with the load to be lifted. Rotation of the pinion 66 also causes rotation of the ratchet wheel 75, but the rotation thereof in this direction is permitted by virtue of the ratchet teeth riding over both the driving pawl 91 and the holding pawl 130, as will be clear from Figure 2.

While we have described above the structure 10 in which the principles of the present invention are preferably embodied, it is to be understood that our invention is not to be limited to the specific details shown and described, but that, in fact, widely different means may be employed in 15 the practice of the broader aspects of our invention.

What we claim, therefore, and desire to secure by Letters Patent is:

1. In a jack, an elongated frame, a lifting member shiftable generally vertically thereon, a rack slideable on said frame, ratchet mechanism for shifting said rack relative to the frame, and means connected between said rack and said lifting member for securing substantially a two 25 to one ratio therebetween.

2. In a jack, an elongated frame, a lifting member including a bell crank having a relatively short arm, a power applying member connected at one end with said arm, a pinion journaled 30 near the other end of said power applying member, a rack fixed to said frame, a second rack slideable longitudinally thereof, said pinion being in mesh with and disposed between said racks, and means for moving said second rack to shift 35 said pinion and said power applying member attached thereto.

3. In a jack, an elongated frame, a lifting member shiftable generally vertically thereon, a rack slideable on said frame, ratchet mechanism for 40 shifting said rack relative to the frame, a second rack mounted on said frame above the first rack, a floating pinion mounted for rolling movement between said racks, and a thrust bar having journal means receiving said pinion and connected 45 with said lifting member.

4. In a jack, an elongated frame, a lifting member shiftable generally vertically thereon, a rack slideable on said frame, ratchet mechanism for shifting said rack relative to the frame, a stationary rack carried by said frame above said first rack, a pair of abutment bars disposed on opposite sides of said stationary rack, a floating pinion mounted between said racks, a thrust rod connected with said pinion and with said lifting member, and ratchet mechanism disposed rearwardly on said lifting frame for shifting said slideable rack, said thrust rod reacting against 50 said abutment bars.

5. In a jack, an elongated frame, a lifting member shiftable generally vertically thereon, a rack slideable on said frame, ratchet mechanism for shifting said rack relative to the frame, and including a pinion journaled in said frame and disposed in mesh with said rack, a second rack 65 fixedly mounted on said frame adjacent said slideable rack, a floating pinion having the same tooth form as said first pinion and meshing with both of said racks, the teeth of said floating pinion bottoming in at least one of said racks to 70 take vertical reactions, and means operatively connecting said second pinion with said lifting member.

6. In a jack, an elongated frame, a lifting member shiftable generally vertically thereon, a rack 75

- slidable on said frame, ratchet mechanism for shifting said rack relative to the frame, and including a pinion journaled in said frame and disposed in mesh with said rack, a second rack 5 fixedly mounted on said frame adjacent said slidable rack, a floating pinion having the same tooth form as said first pinion and meshing with both of said racks, said pinions being of the same size and disposed closely adjacent one another 10 when the floating pinion is adjacent the rear end of said fixed end, and a thrust rod reacting against said frame and adapted to receive the first pinion to transmit lifting force to said lifting member.
- 15 7. In a jack, an elongated frame comprising spaced side plates having substantially horizontal upper edges, a lifting member mounted between said side plates at one end of the frame for pivotal movement about a low fulcrum point and having a forwardly extending lifting arm and a relatively short downwardly extending power arm, a load receiving saddle carried at the outer end of said lifting arm, a rack bar slidably carried by the frame between said side plates, ratchet and pinion means for shifting said rack bar, a second rack bar fixedly carried by said frame above said first rack bar, a floating pinion disposed between said rack bars and in mesh therewith, and a downwardly and forwardly extending thrust bar connected at its forward end with said power arm and carrying said pinion at its rear end.
8. In a jack, raising and lowering means including a shaft and auxiliary means for operating the same including a member movably mounted on said shaft, and an operating member extending beyond said first member in power receiving position and movably mounted on said first member and having a releasable connection with said shaft for rotating the same independently of the operation of said raising and lowering means.
9. In a jack, raising and lowering means including a shaft, and auxiliary means for operating the same including a toothed wheel fixed to the shaft, a support pivotally mounted on the shaft adjacent said wheel, and a lever pivotally mounted on said support for movement relative thereto into and out of engagement with said toothed wheel and operative during said engagement to impart rotation to both said support and said shaft.
10. In a jack, an elongated frame, a lifting member at one end thereof, a longitudinally disposed thrust rod connected with said member, a rack bar operatively connected with said thrust rod for shifting the same, a pinion meshing with said rack bar, a ratchet wheel separated from but disposed in direct engagement with said pinion, and means for driving said ratchet wheel.
11. In a jack, an elongated frame, a lifting member at one end thereof, a longitudinally disposed thrust rod connected with said member, a rack bar operatively connected with said thrust rod for shifting the same, a pinion meshing with said rack bar, a shaft on the frame supporting said pinion, a ratchet wheel having a hub portion directly engaging the teeth of said pinion for rotating the same, and means for driving said ratchet wheel.
12. In a jack, an elongated frame, a lifting member at one end thereof, a longitudinally disposed thrust rod connected with said member, a rack bar operatively connected with said thrust rod for shifting the same, a pinion meshing with said rack bar, a shaft on the frame and extend-
- ing therefrom at one end, said pinion being non-rotatably supported on said shaft, a ratchet wheel having means directly engaging portions of said pinion for driving the same, pawl means for driving said ratchet wheel, and auxiliary means on said shaft for driving the pinion independently of said ratchet wheel and pawl means.
13. In a jack, a lifting member, lifting mechanism including a shiftable ratchet member and holding and lifting pawls for raising said lifting member, a slidable reversing member, means biasing said reversing member for movement in one direction, and releasable locking means for said reversing member, the latter being adapted when released for progressively positioning said pawls to lower said lifting member.
14. In a jack, a frame, a lifting member, raising and lowering mechanism including a shiftable ratchet member and lifting and holding pawls disposed on the lower side of said ratchet member adjacent one another, a reversing member mounted in the lower portion of said frame for sliding movement relative thereto and operative in one position to free said pawls to provide for raising said lifting member and operative in another position to control said pawls to provide for lowering said lifting member, and means for shifting the position of said reversing member.
15. In a jack, an elongated frame, a lifting member at one end of said frame, raising and lowering mechanism at the other end including longitudinally movable rack means operatively connected with said lifting member, a housing enclosing said mechanism, a ratchet wheel associated with said rack, lifting and holding pawls disposed on the lower side of said ratchet wheel and in longitudinally spaced relation, a reversing cam member slidably mounted on the frame longitudinally thereof and adapted to be shifted into operative engagement with said pawls to provide for lowering the lifting member, said pawls, ratchet wheel and cam member being mounted in the lower portion of said housing, a quadrant supported on said frame for pivotal movement about the axis of said ratchet wheel, said quadrant having an opening formed therein and said lifting pawl being carried by the quadrant and positioned below the opening therein, and means engageable in said opening for shifting said quadrant.
16. In a jack, an elongated frame, a lifting member at one end thereof, a longitudinally disposed operating member connected with the lifting member, a slotted housing near the other end of said frame, raising and lowering mechanism disposed within said housing and connected with said operating member and including a part extending from the housing through the slot therein, and an operating handle movably mounted exteriorly of the housing and having means engageable with said extended part of the raising and lowering mechanism.
17. In a jack, an elongated frame, a lifting member at one end thereof, a longitudinally disposed operating member connected with the lifting member, a slotted housing near the other end of said frame, said housing comprising upper and lower sections, raising and lowering mechanism disposed within said housing and connected with said operating member, one of said housing sections being detachable to facilitate assembly of said raising and lowering mechanism, and means disposed in the slot in said housing for operating said raising and lowering means.

18. In a jack, an elongated frame, a lifting member at one end thereof, a longitudinally disposed operating member connected with the lifting member, a slotted housing near the other end of said frame, raising and lowering mechanism disposed within said housing and connected with said operating member and including a longitudinally shiftable member extending from said housing, and a cover for said shiftable member carried by said housing and including a part disposed in the slot in the housing.

19. In a jack, an elongated frame, a lifting member at one end thereof, a longitudinally disposed operating member connected with the lifting member, a slotted housing near the other end of said frame, raising and lowering mechanism disposed within said housing and connected with said operating member, said mechanism including an operating member having laterally spaced portions extending through the slot in said housing and a longitudinally shiftable member extending from said housing, and a cover for said shiftable member carried by said housing and including a part disposed in the slot in the housing between the laterally spaced portions of said operating member.

20. In a jack, raising and lowering means including a shaft, an auxiliary means for operating the shaft including a member movably mounted on the frame, means carried by said member and having an outwardly extending force receiving end disposed outwardly of said member and an inner end disposed adjacent said member and adapted to rotate the shaft in one direction, and means for shifting the last named means out of engagement with said shaft.

21. In a jack, raising and lowering means including a shaft, an auxiliary means for operating the shaft including a member mounted for limited motion about the axis of said shaft, a second member movably mounted on said first member and adapted in one position to be operatively connected with the shaft to rotate the same and in another position to be released from operative

engagement with the shaft, spring means biasing the first member for movement toward a given position about its axis of movement, and biased means reacting against said first member and serving to hold said second member in said inoperative position.

22. In a jack, raising and lowering means including a shaft, an auxiliary means for operating the shaft including a member movably mounted with respect to the frame about the axis of said shaft, a second member movably mounted on said first member and adapted in one position to be operatively engaged with said shaft and in another position to be out of operative engagement therewith, means biasing said first member for movement to a given position, and biasing means acting between said first and second members for holding the latter in a given position with respect to the first member, said first biasing means being stronger than said second biasing means, whereby when said second member is operated the second biasing means is overcome and said second member is initially moved into operative engagement with said shaft, additional movement imparted to said second member serving to shift both the shaft and said first member.

23. In a jack, a frame, a lifting member, raising and lowering mechanism including a ratchet member and lifting and holding pawls disposed on the lower side of said ratchet member adjacent one another, a slidably reversing member carried by the frame and operative in one position to free said pawls to provide for raising said lifting member and operative in another position to control said pawls to provide for lowering said lifting member, spring means biasing said member for movement in one direction, and locking means for holding said reversing member in another position against the bias of said spring means.

SIGMUND MANDL.
EDWARD M. PFAUSER.
